UNITED STATES PATENT OFFICE.

ANNIE L. BLISS, OF SPRINGFIELD, MASSACHUSETTS.

DESIGN FOR A BROILER.

SPECIFICATION forming part of Design No. 32,538, dated April 17, 1900.

Application filed January 9, 1900. Serial No. 896. Term of patent 7 years.

To all whom it may concern:

Be it known that I, ANNIE L. BLISS, a citizen of the United States of America, residing at Springfield, in the county of Hampden and State of Massachusetts, have invented a new and original Design for a Broiler, of which the following is a specification, reference being had to the accompanying drawings, forming a part hereof.

My design relates to the class of cooking utensils which are generally employed for broiling, boiling, toasting, &c., and are usually placed on top of an ordinary stove, the draft being downwardly into the stove, charcoal being placed in the basket-like portion of the device.

In the drawings, Figure 1 is a plan view, and Fig. 2 is a side view.

As shown in the drawings, the leading or material feature of my design consists of a dish-shaped device having side walls in its top portion of greater diameter than its lower portion and with the side walls and bottom of the lower depending portion provided with openings.

Having described my invention, what I claim, and desire to secure by Letters Patent, is—

The design for a broiler, as herein shown and described.

ANNIE L. BLISS.
